UNITED STATES PATENT OFFICE.

CHARLES H. RADCLIFFE, OF ELGIN, ILLINOIS.

WATER-GUN.

SPECIFICATION forming part of Letters Patent No. 740,371, dated September 29, 1903.

Application filed October 6, 1902. Serial No. 126,045. (No model.)

To all whom it may concern:

Be it known that I, CHARLES H. RADCLIFFE, a citizen of the United States of America, and a resident of Elgin, Kane county, Illinois, 5 have invented a certain new and useful Improvement in Water-Guns, of which the following is a specification.

My invention relates to improvements in guns adapted to discharge a stream of water 10 from the rear end of the barrel into the face of the operator when the trigger is pulled. Guns of this character are used in initiating new members into secret societies. The gun has all the appearances of an ordinary fire- 15 arm, and consequently the candidate for admission into the secret society thinks that the usual report will follow the pulling of the trigger. However, when the trigger is pulled the candidate receives a spray or stream of 20 water full in the face, much to the amusement of the onlookers.

Generally stated, the object of my invention is to provide a simple, efficient, and highly-improved gun of this character.

25 A special object is to provide a gun of this description which may be discharged a number of times without reloading.

Another object is to provide an improved arrangement whereby the gun may be easily 30 loaded with water or other fluid.

It is also an object to provide certain features and details of improvement tending to increase the effectiveness and serviceability of a device of this particular character.

35 To the foregoing and other useful ends my invention consists in matters hereinafter set forth and claimed.

In the accompanying drawings, Figure 1 is a longitudinal section of my improved water- 40 gun, the barrel and also a portion of the stock being broken away for convenience of illustration. Fig. 2 is a longitudinal section of the forward end of the gun-barrel. Fig. 3 is a similar view of the rear end of the plunger. Fig. 4 is a similar view of the rear end of the gun-barrel. Fig. 5 is a bottom view of the device for pulling back the trigger. Fig. 6 is a section on line 6 6 of Fig. 2. Fig. 7 is a section on line 7 7 of Fig. 1. Fig. 8 is a perspective of the device shown in Fig. 5.

As thus illustrated, my improved gun com-

prises a barrel A and a stock B. The said barrel can be secured to the said stock in any suitable manner and can have its muzzle or forward end partially closed by a cap a. In 55 accordance with the purposes of the gun the rear end of the barrel is preferably provided with a small valved discharge-opening a. The plunger C for ejecting the water from the rear of the gun is preferably tubular in form 6c and provided at each end with a valve. The valve c opens inwardly under the pressure of the instrument inserted through the muzzle of the gun, while the valve c' opens outwardly. A rod c² is provided as a means for opening 65 the valve c'. The rear end of the tubular plunger is preferably provided with a small packing-ring c³, so as to adapt it to serve as a head for ejecting the water from the chamber a². The spring D, which incloses the 70 plunger and which is interposed between a shoulder c⁴ on the plunger and a shoulder a³ on the gun-barrel, tends to keep the plunger-head normally against the rear end of the gun-barrel. A projection c⁵ is preferably se- 75 cured to the plunger and adapted to slide in a slot a⁴ in the gun-barrel. A sliding piece E, having a slot e, adapted to receive the pro- 80 jection c⁵, is provided and arranged for move- ment between the gun-barrel and the stock. The trigger F can be of any suitable charac- 85 ter and is adapted to engage the said projec- tion c⁵.

In order that the gun may have all the ap- 85 pearances of an ordinary firearm, the rear end of the gun-barrel is preferably provided with a socket a⁵, adapted to receive a cartridge X. Covering the socket is a pivotal hammer G, provided with a spring-pressed catch g. The rear discharge-opening a' is continued by the 90 opening g' through this hammer. Thus the rear end of the gun-barrel is provided with what may be termed a "dummy hammer," whereby the candidate for admission to the secret society is led to believe that a real fire- 95 arm is being loaded. In loading the gun, a suitable instrument is preferably inserted through the muzzle of the gun, so as to open the valve c', and the plunger is then filled with water. It will also be observed that by 100 cocking the gun—that is to say, drawing the plunger back to the position shown in Fig. 1—

both valves can be opened simultaneously, so as to not only permit the filling of the plunger, but also so as to permit the chamber a^2 to be filled, it being observed that an inward movement of the valve C causes the rod c^2 to open the valve c' . In cocking the gun, as explained, the sliding piece e is employed for drawing back the plunger, so as to allow the trigger to engage the projection c^5 , and the said sliding piece is then returned to its normal position, as shown in Fig. 1. After this the gun can then be discharged by pulling the trigger, so as to allow the spring-pressed plunger to eject the water from the rear discharge-passages. At this juncture it will be understood that the passage a' is provided with a spring which readily yields under the pressure of the water being ejected. Thus the object of this valve is only to prevent the ejection before the gun is discharged.

Now to reload the chamber a^2 from the magazine provided by the hollow plunger it is only necessary to again employ the sliding piece E for drawing back the plunger, an extreme movement of the plunger causing the rod c^2 to open the valve c' sufficiently to admit a part of the contents of the plunger to be transferred to the chamber a^2 . In this way the cocking of the gun, or, in other words, the drawing back of the plunger, serves to automatically fill the chamber a^2 from the magazine. The gun is then ready for another discharge. Before handing the gun to the candidate, however, the fake hammer G is first pulled back, it being held in its rigid position by the catch g , and a cartridge is then inserted in the socket in the rear of the gun-barrels. The hammer is then returned to the position shown in Fig. 1, after which the gun is ready to be fired by the candidate.

It will be readily understood that the different valves can be of any suitable or approved character. The valve c' is, however, preferably provided with openings 1, which are uncovered by the rear end of the tube when the valve is pushed outwardly by the rod c^2 . This valve is held normally closed by the spring 2. A similar spring 3 is also employed for holding the valve c normally closed. Any suitable appliances may be employed for opening the valves and filling the gun.

What I claim as my invention is—

1. A water-gun provided with a rear discharge-opening, having also a hollow spring-actuated plunger adapted to provide a magazine-chamber, and a trigger for holding and releasing said plunger, and an outwardly-opening valve in the rear end of the plunger and means for opening the same.

2. A water-gun provided with a rear discharge-opening, and having also a magazine-chamber capable of holding a plurality of charges whereby the gun may be discharged a number of times without reloading, and a suitable trigger and ejecting mechanism, said

ejecting mechanism involving a spring-actuated plunger adapted to be held and released by said trigger, and an outwardly-opening valve in the rear end of said magazine-chamber and means for opening the same. 70

3. A water-gun provided with a rear discharge-opening, and having also a tubular spring-impelled plunger with a valve at each end, and a trigger for holding and releasing the plunger, the valve at the forward end of the plunger opening inwardly, the valve at the rear end of the plunger opening outwardly, and means for operating said valves. 7

4. A water-gun provided with a rear discharge-opening, and having also a tubular spring-actuated plunger provided with a valve at each end, a member having a sliding connection with the said plunger, said member thereby being adapted to draw the plunger in a position to discharge the water and to then be returned to its normal position, and a trigger for holding the plunger in position to eject the water and adapted to release the plunger when pulled, the valve at the forward end of the plunger opening inwardly, the valve at the rear end of the plunger opening outwardly, and means for operating said valves. 85

5. A water-gun provided with a valved discharge-opening, and having a tubular spring-impelled ejecting-plunger constructed with a valve at its rear end, and a trigger for holding and releasing the plunger, together with means for opening the valve at the rear end of the plunger to permit the water to pass from the latter into the discharge-chamber. 95

6. A water-gun provided with a rear discharge-opening, and having a tubular spring-actuated plunger adapted to hold a suitable quantity of water, the rear end of said plunger being provided with a valve whereby suitable charges are allowed to escape and accumulate in a position to be ejected by the plunger, and a trigger for holding and releasing the plunger, together with means for opening the valve at the rear end of the plunger to permit the water to pass from the latter into the discharge-chamber. 105

7. A water-gun provided with a rear discharge-opening, and having a tubular spring-impelled plunger adapted to hold the water, the head of said plunger being provided with a valve operable from the muzzle of the gun, and a trigger for holding and releasing the said plunger. 115

8. A water-gun provided with a rear discharge-opening, and having a tubular spring-actuated plunger provided with a valve at each end, both of said valves being simultaneously operable from the muzzle of the gun, and a trigger for holding and releasing the plunger. 125

9. A water-gun provided with a rear discharge-opening, a tubular spring-actuated plunger provided at each end with a valve, said valves being operable from the muzzle 130

of the gun, a coil-spring surrounding the said plunger, and a trigger adapted to catch and hold the plunger in a position to eject the water and adapted when pulled to release the plunger.

10. A water-gun provided with a rear discharge-opening and ejecting mechanism, trigger mechanism for holding and releasing the ejecting mechanism, and a fake cartridge device.

11. A water-gun provided with a discharge-opening, and having suitable trigger and ejecting mechanism, and constructed with a socket adapted to receive a cartridge.

12. A water-gun provided with a rear discharge-opening, and having suitable trigger and ejecting mechanism, and also construct-

ed with a dummy hammer and socket adapted to receive a cartridge.

13. A water-gun constructed with a rear discharge-opening, and having a spring-impelled plunger and magazine, a valve device at the rear end of the plunger, and means for operating said valve whereby the gun is automatically loaded and made ready for discharge when the plunger is cocked, and trigger mechanism for holding and releasing the plunger.

Signed by me at Elgin, Kane county, Illinois, this 22d day of September, 1902.

CHARLES H. RADCLIFFE.
